[57] CLAIM

The ornamental design for an X-ray apron holder, as shown and described.

DESCRIPTION

FIG. 1 is a front and left side perspective view of an X-ray apron holder showing our new design, the right side being a mirror image of the left side;

FIG. 2 is a similar view to FIG. 1 showing the X-ray apron holder in a stored configuration with surrounding structure drawn in broken lines;

FIG. 3 is an end elevation view of FIG. 1;

FIG. 4 is a similar view to FIG. 2 with no surrounding structure; and,

FIG. 5 is an end elevation view of FIG. 4.

The broken line showing is for illustrative purposes only and forms no part of the claimed design.

The surface(s) or portion(s) not shown in the drawing or described in the specification form(s) no part of the claimed design.

The bottom of the article is plain and unornamented.
